UNITED STATES PATENT OFFICE

2,259,176

INTERNAL COMBUSTION ENGINE

Earl H. Pitney, Willmar, Minn.

Application October 2, 1939, Serial No. 297,418

3 Claims.

(Cl. 74—44)

This invention relates to internal combustion engines, and more particularly to the driving connections between the pistons and crank shaft.

It is an object of my present invention to provide simple and thoroughly practical mechanism for connecting the crank shaft of an internal combustion engine with the pistons in such manner as to materially increase the efficiency or output of the engine.

More specifically, it is an object to provide mechanism connecting the crank shaft with the connecting rods of the several pistons and controlling the effective locations of such connections throughout the various piston strokes, to the end that the crank arms at the topmost and lowermost positions of the piston have passed dead center positions, and further to the end that a lag is produced in the movement of the pistons as the crank arms reach and pass dead center positions.

The foregoing operations are effected by a novel, shiftable, eccentric connection between the crank pin and the connecting rod in cooperation with a means actuated by the crank movement and swinging of the connecting rod that controls the position of the eccentric throughout the up and down strokes of the piston.

As a result of the stated operation and functions of my mechanism, several definite advantages, all improving the efficiency or output of an internal combustion engine, are obtained, to wit:

(1) The effective angle of thrust upon the crank when the piston is at its topmost position and pressures are at maximum is improved over that of engines now in wide use, and greater leverage is obtained in the down stroke, although the length of the stroke is unchanged.

(2) The speed of the piston's down stroke is more closely matched to the rapidly diminishing pressure in the cylinder above, which means better absorption of power and, therefore, less knocking or "pinging."

(3) The effect is to distribute the flow of power somewhat similar to an increase in the number of cylinders applied to an internal combustion engine.

(4) Better control of the volume of air and/or gas mixture is obtained because of the piston's lag at the bottom of the intake stroke. This is of a special advantage where an engine is working in high altitude.

(5) Burned gases are better scavenged from the cylinder because of the piston's lag at the top of the exhaust stroke.

(6) Cooler running is assured because even with faulty timing, burning gases are not compressed in the compression stroke and the heat of combustion is spread more evenly over the entire stroke.

(7) Upon firing, pistons and rings move faster initially than with conventional structure, and consequently do not subject the oil film between the cylinder and the rings to the combination of slow movement and high pressures and temperature.

(8) The effective length of the crank arm is increased during the greater part of the power stroke, although no change in the actual stroke itself.

These and other objects and advantages of my invention will be more apparent from the following description made in connection with the accompanying drawing, wherein like reference characters refer to the same parts throughout the several views, and in which:

Fig. 1 is a vertical section through an internal combustion engine of the four-cycle type taken through one of the cylinders and having incorporated therein an embodiment of my invention;

Fig. 2 is a fragmentary cross section on a somewhat larger scale taken on the line 2—2 of Fig. 1; and

Figs. 3 and 4 are diagrammatic views illustrating my improved mechanism in the position of the piston in the middle of its compression stroke and in the middle of its firing stroke respectively.

In the drawing, my improved mechanism is shown as applied to a conventional type of four-cycle internal combustion engine having the usual cylinder C provided with a surrounding water jacket W, and having working within said cylinder the reciprocating piston P connected by wrist pin WP with the connecting rod CR. Crank case CC having the usual top T on which the cylinders are rigidly mounted is also shown. A conventional type of crank shaft CS having the usual crank pin CP is mounted for revolution below the cylinders in the crank case.

My invention, as in the embodiment illustrated, comprises mechanism forming an actuating driving connection between the lower end of the connecting rod and the crank shaft.

In the embodiment illustrated I provide an eccentric connection between the connecting rod CR and crank pin CP which includes an eccentric in the form of a disc 6 having an eccentrically disposed bearing 6a therein, in which the crank pin is journaled. The eccentric disc 6 has its periphery journaled in a relatively large split

bearing rigidly connected with the connecting rod R. The bearing is preferably channeled, as clearly shown in Fig. 2, to properly engage the complementary shaped periphery of disc 6.

Eccentric disc 6 is shifted in an oscillatory manner throughout the up and down strokes of piston P for the purpose of changing the relative positions of the connecting rod with the center of crank pin CP during the revolution of the crank shaft. To this end an actuating link 8 having its outer end pivotally connected by a rugged journal bolt 9 to a suitable lug or mounting 10, as shown on the crank case, is pivotally connected at its inner end with a shift arm 6b integrally formed or rigidly connected with disc 6. Disc 6 is cut along the line of a chord 6x to permit clearance of link 8 in the lower positions of the crank shaft.

It will be noted that eccentric 6, crank pin CP, and actuating link 8 are so proportioned and related that at the uppermost position of the piston when firing occurs, the crank arm has passed dead center position. In the downward firing stroke of the engine, eccentric 6 is moved counterclockwise due to the action of the crank shaft in clockwise movement and the actuating link 8 (see Fig. 4). As the piston approaches the lower end of its stroke (see dotted line position in Fig. 1), link 8 causes the eccentric 6 to be moved for a small portion of a rotation in clockwise direction, thereby producing a lag in the movement of the piston. Thus it is seen that at the start of the firing stroke, the piston moves rapidly because of the greater leverage on the crank arm and the angularity between it and the connecting rod, and the down stroke is more perfectly matched in its application of force to the crank shaft with the diminishing expansion force of the explosion, and consequently with better driving efficiency.

It will further be seen that during the time the piston reaches and holds its downward limit of travel, the crank arm passes its dead center position for the beginning of the upward stroke. Greater leverage is obtained in the down stroke, where desired, than in the up stroke. In the up or exhaust stroke (see Fig. 3) as the piston approaches its upward position, lag again occurs giving burned gases a greater chance to be completely exhausted. In the next down stroke of the piston, the intake stroke, the lag at the lower end of the piston's travel affords a better control of volume of air and/or gas admitted, which is of special advantage where the engine is working at high altitude. On the next, or compression up stroke, the compression is held at a maximum in the position shown in Fig. 1, while the crank arm passes dead center position and until firing occurs. Also, the disc could be so positioned as not to attain maximum compression until after dead center.

In the embodiment illustrated (see Fig. 1) the piston in its up strokes, both compression and exhaust, remains in its topmost position, indicated in full lines, during the movement of the crank arm and crank pin through the arc A due to the fact that the axis of the eccentric disc 6 is simultaneously swung in the opposite direction through the arc B.

From the foregoing it will be seen that with my structure the application of power upon the crank shaft at a more effective angle during firing stroke, the effectiveness of the lag in completing the exhaust stroke, the advantages in better control of the combustive mixture, and the

distribution of the flow of power due to matching speed of the piston's down stroke more evenly with the diminishing pressure in the cylinder above, all bring about a substantial increase in the efficiency of the engine output which I estimate to be from 20% to 30% over conventional types of internal combustion engines now in use. My invention is, of course, applicable to compressors, air motors and other types of analogous devices as well as to all types of internal combustion engines.

Adapted to compressors, more time will be given the gas to escape from the cylinder and more on the intake stroke because of the lag which has been referred to, and will result in a cooler operating unit meaning much greater efficiency.

It will, of course, be understood that various changes may be made in the form, details, arrangement and proportions of the parts without departing from the scope of my invention.

What is claimed is:

1. In an internal combustion engine, the combination with a cylinder, a crank disposed below said cylinder, a piston reciprocably mounted in said cylinder, a wrist pin and a connecting rod, of a mechanism for changing the relative position of the connecting rod with reference to the center of the crank pin during the revolution of the crank shaft comprising, an oscillatory member having a purely pivotal connection with the lower end of said connecting rod and having an eccentrically disposed bearing in which the pin of said crank is journaled, and an actuating torque connection having one of its ends connected with said oscillatory member at a point eccentric to said pivotal connecting rod connection and also eccentric to said crank pin bearing and adjacent the longitudinal center line of said connecting rod when said piston is in uppermost position, said torque connection extending transversely of the axis of said crank and having its outer end pivoted to an anchoring member disposed at some distance to one side of the longitudinal center line of said piston, the length of said torque connection and its relation to said oscillatory member and the bearing for said crank pin being such that in the reciprocation of said piston a lag occurs in the upper movement thereof and said crank pin moves past dead center relation with the axis of said crank and said wrist pin before said piston starts its downward movement, and that the downward movement of said piston is relatively rapid during the first part of its downward stroke, gradually decreasing in speed toward the lower portion of its downward stroke.

2. In an internal combustion engine, the combination with a cylinder, a crank disposed below said cylinder, a piston reciprocably mounted in said cylinder, a wrist pin and a connecting rod, of a crank connection shifting member having a purely pivotal connection with said connecting rod and having a bearing disposed eccentrically of said pivotal connection in which the pin of said crank is journaled, and an actuating torque connection pivotally connected with said shifting member at one of its ends and pivoted to anchoring means at its opposite end for shifting the position of the pivotal connection of said crank pin with said connecting rod transversely of said rod during revolution of said crank to provide for relatively rapid movement of said piston during the first part of its downward stroke and a lag of said piston in its ex-

treme upper movement, and movement of said crank pin past dead center relation between the crank axis and wrist pin before said piston is moved past uppermost position.

3. In an internal combustion engine, the combination with a cylinder, a crank disposed below said cylinder, a piston reciprocably mounted in said cylinder, a wrist pin and a connecting rod, of a crank connection shifting disc having a purely pivotal connection with said connecting rod and having a bearing disposed eccentrically of said pivotal connection in which the pin of said crank is journaled, and an actuating torque link having one of its ends connected with said disc for applying torque thereon, said torque connection being at a point adjacent the line of said connecting rod when said piston is in upper-

most position, said link extending transversely of the axis of said crank and being disposed substantially horizontal when said piston has completed half its stroke, the other end of said torque link being pivoted to an anchoring member disposed at some distance to one side of the longitudinal center line of said piston, the relationship of said crank pin bearing to the torque connection of said link in cooperation with the recited structure causing relatively rapid movement of said piston during the first part of its downward stroke and a lag of said piston in its extreme upper movement and movement of said crank pin past dead center relation between the crank axis and wrist pin before said piston is moved past uppermost position.

EARL H. PITNEY.
